(**) Term: **14 Years**

(57) **CLAIM**

The ornamental design for a server cover, as shown and described.

DESCRIPTION

FIG. 1 is a perspective view taken from the top and right side of a server cover showing our new design;

FIG. 2 is a front elevational view thereof;

FIG. 3 is a right side elevational view thereof;

FIG. 4 is a left side elevational view thereof; and,

FIG. 5 is a top plan view thereof.

The broken lines are shown in the views for illustrative purposes only and form no part of the claimed design.
